UNITED STATES PATENT OFFICE.

CHARLES BURT CLARK, OF EAST ORANGE, NEW JERSEY.

ELECTRIC-LAMP SOCKET.

1,153,195.

Specification of Letters Patent. Patented Sept. 14, 1915.

Application filed June 4, 1914. Serial No. 842,870.

To all whom it may concern:

Be it known that I, CHARLES BURT CLARK, a citizen of the United States, residing at East Orange, in the county of Essex and 5 State of New Jersey, have invented certain new and useful Improvements in Electric-Lamp Sockets, of which the following is a specification.

This invention relates to an improvement 10 in holders or supports for electric lamps and the shades accompanying the same, and its novelty consists in the construction and adaptation of the parts as will be more fully hereinafter pointed out.

15 The object of the invention is to provide a simple, economical and efficient means for supporting the insulating base into which the usual socket of an electric lamp is inserted and simultaneously supporting a lamp 20 shade or globe, such as is used with such lamps, and to provide means for varying the size of the globe without changing the other parts of the device.

A further object of the invention is to so 25 construct the parts that the insulating base of the electric lamp and the shade holder may be removed from the support without disturbing the electrical conducting connections.

30 In the drawings, Figure 1 is a central longitudinal section of a device embodying the invention. Fig. 2 is a perspective of the stepped supporting annulus. Fig. 3 is a perspective of the insulating base and holder, 35 and Fig. 4 is an elevation of the globe holder showing a portion of the globe secured therein.

In the drawings, 10 is a hickey of any 40 suitable form through which the electric conductors leading to the lamp are passed in the usual manner.

45 11 is an externally threaded pipe engaged with the threads of the hickey and supported therefrom, and from which the other parts as hereinafter described are suspended.

Arranged beneath the hickey is a support 50 12 in the form of a stepped annulus provided with a centrally threaded aperture 13. The upper step of the annulus is externally threaded as indicated at 14, and the lower step of the annulus which is of smaller diameter is externally threaded as indicated at 15. It is also provided with an annular groove or recess 16 to reduce its weight, and on its 55 lower surface it is provided with downwardly projecting positioning pins indicated

at 17. In effect it comprises two externally threaded disks with a common central aperture the larger disk superimposed upon the smaller and the whole piece made integral.

Secured to and depending from the lower step of the annulus 12 is the insulating socket support 20. It comprises a cylindrical casing open at the top and bottom and internally threaded at the top as indicated 60 at 21 to engage the external threads on the lower step of the annulus. Near its bottom it is provided with an inwardly extending annular flange 22 below which it is provided with an outwardly extending reverted annular flange 23 forming a lower terminal or bead.

Within the support 20 is arranged an insulating socket 30 which is of any suitable form. Any of the forms common to the art 75 may be employed, but whatever one is employed should be provided with diametrically arranged notches 31 and 32 at its upper edge, these being adapted to be engaged by the positioning pins 17 projecting downward from the annulus 12, and it should also be provided with a shoulder as indicated at 33 whereby it may rest by gravity upon the annular flange 22 of the support 20. It should, of course, be provided with 80 the usual threaded metallic sleeve to receive the lamp and with the necessary electrical conductors, which should be connected in the manner usual to the art, with the conductors passing down from the hickey through 85 the inside of the device to the socket. These insulating sockets can be purchased in the open market and form no part of my invention and their construction is, therefore, only referred to in so far as it is relevant to an 90 understanding of the present invention.

A globe support 40 of general cylindrical form, open at the top and bottom and internally threaded at its upper end as indicated at 41 is secured by means of such 100 threads to the upper step of the annulus 12. At its lower end it is expanded to form a depending flange 42 adapted to receive the usual globe 43 and is provided with clamping screws 44 to hold the globe in place. At 105 the place where it is expanded from the general cylindrical form as indicated at 45 there is formed quite a substantial shoulder upon which is placed and which is adapted to receive the lower rim or edge 46 of a 110 canopy 47, which is adapted to conceal the other parts of the device and to form an

ornamental element, which extends to the ceiling or other place against which the entire device is secured.

It will be understood that variations may be made in the constructive details of this device without departing from its essential purpose and that it is not necessary that the globe support or the insulating socket support should be secured to the annulus by screw threads or that the hickey or other form of support for the entire device should be secured to such annulus by a threaded pipe.

Other forms of connections rigid enough for the purpose and usual to the art and equivalent to the connection stated may be employed if the conditions of the use of the device render it expedient to do so.

The globe support 40 may be made of any diameter at the bottom where it is expanded to form the flange 42, and therefore may be adapted for use with a lamp shade or globe having any diameter at its upper edge where it is engaged by and supported upon such flange 42. It is necessary, however, that the diameter of the upper threaded portion 41 of the shade holder shall remain constant in order that it may properly engage the external threads 14 of the upper step 30 of the annulus 12.

I claim:

1. A combined electric lamp socket and shade holder, comprising a stepped annulus having an internally threaded central aperture, and two externally threaded steps, a hollow cylindrical socket holder threaded on the lower step and a hollow cylindrical shade holder threaded on the upper step.

2. A combined electric lamp socket and shade holder, comprising a stepped annulus having an internally threaded central aperture, and two externally threaded steps, a hollow cylindrical socket holder threaded on the lower step and a hollow cylindrical shade holder threaded on the upper step, the lower step being provided with means to engage the socket within the holder to prevent the rotation of the latter.

3. A combined electric lamp socket and shade holder, comprising a stepped annulus

having an internally threaded central aperture, and two externally threaded steps, a hollow cylindrical socket holder threaded on the lower step and a hollow cylindrical shade holder threaded on the upper step, the lower step being provided with means to engage the socket within the holder to prevent the rotation of the latter consisting of downwardly projecting positioning pins.

4. A combined electric lamp socket and shade holder, comprising a stepped annulus having an inner central aperture, means for connecting the annulus at said aperture with a support, a socket holder and means for connecting it to the lower step of the annulus, a shade holder and means for connecting it with the upper step of the annulus.

5. In combination a hickey, an annulus arranged beneath the same and supported therefrom, a socket holder, a connection between it and the annulus, a shade holder and a connection between it and the annulus, a socket in the holder and means on the top to engage the socket to prevent its rotation.

6. A combined electric lamp socket and shade holder, consisting of an internally threaded annulus and means for connecting the annulus with a support, a socket holder and a shade holder, said annulus provided with a plurality of externally threaded portions arranged for supporting the socket holder within the shade holder.

7. A combined electric lamp socket and shade holder, comprising an annulus having a central aperture and provided on its periphery with threaded portions, said portions being of different diameters, means for connecting the annulus at said aperture with a support, a socket holder and means for connecting it to the smallest threaded portion of the annulus, a shade holder and means for connecting it to the largest threaded portion of the annulus.

In testimony whereof I affix my signature in presence of two witnesses.

CHARLES BURT CLARK.
